DESIGN FOR AN APPOINTMENT PAD

Denver M. Wright, Brentwood, Mo.

Application July 29, 1939, Serial No. 86,323

Term of patent 7 years

To all whom it may concern:

Be it known that I, Denver M. Wright, a citizen of the United States, residing at Brentwood, in the county of St. Louis and State of Missouri, have invented a new, original, and ornamental Design for an Appointment Pad, of which the following is a specification, reference being had to the accompanying drawing, forming part thereof.

Fig. 1 is a top view of an appointment pad showing my new design.

Fig. 2 is a side view of the same.

I claim:

The ornamental design for an appointment pad, as shown.

DENVER M. WRIGHT.
